UNITED STATES PATENT OFFICE.

ANDREW G. LUND, OF ST. PAUL, MINNESOTA.

RECORD-SHEET HOLDER AND PROTECTOR.

Application filed December 2, 1921. Serial No. 519,545.

To all whom it may concern:

Be it known that I, ANDREW G. LUND, a citizen of the United States, residing at St. Paul, in the county of Ramsey and State of Minnesota, have invented a new and useful Record-Sheet Holder and Protector, of which the following is a specification.

This invention relates to devices for holding and protecting record sheets and similar papers while they are being filled out in writing, and the object is to provide an improved article of said class. To demonstrate, in the accompanying drawings, the of my device I have shown it as in use for holding a bunch of blanks upon which the time a mechanic or laborer works is recorded each day.

In said drawings Fig. 1 is a face view of my device with time record sheets held in it.

Fig. 2 is a section on line 2—2 in Fig. 1. Fig. 3 is a view looking upward at the lower left corner of Fig. 1.

Fig. 4 is a section on line 4—4 in Fig. 1.

Fig. 5 is Fig. 4 modified.

Fig. 6 is a section on line 6—6 in Fig. 7.

Fig. 7 is a contracted face view of the device with some modifications.

Fig. 8 is a face view of the device with modifications.

Fig. 9 is a bottom edge view of Fig. 8.

Fig. 10 is Fig. 9 modified. Fig. 11 is a modified face view of the main parts of a further modification on a much reduced scale.

Referring to the drawings by reference numerals, 1 designates the main body of the device and may be made of wood or aluminum or other sheet metal. In Fig. 1 said body is formed at its upper end with a roll 2 in which is hingedly inserted the middle portion 3 of a wire having its end portions sloped downward at 4 and therebelow formed into two parallel arms 5 having their ends 6 extended slightly below the lower

edge of the body plate and are held in operative position by being sprung inward and allowed to spread into hooks 7 formed of the lower corners of the plate. The vertical edges of the plate are formed with angular flanges 8 to stiffen the plate and guard the contents placed upon it. 9 is merely a hole in the plate to enable it to be hung on a peg when not in use. The plate is further provided with guard posts 10 and 11 and sharp

prongs 12 (see Fig. 4).

Slidably engaging the straight arms 5 are

the ends of a resilient sheet-metal guard 13, which is provided with embossments 14 for the operator's fingers to engage in moving the guard up and down. The upper and lower edges of the guard plate 13 are straight, parallel and extend horizontally across the body plate so as to be readily used as straight-edges in drawing horizontal lines upon the paper held between the body plate and the guard plate, like the bunch of "time report" sheets 15 (see Figs. 1, 2 and 4).

As my device is eminently suitable for holding the kind of blanks known as the "Standard daily time report" blanks, I have shown such blanks in Fig. 1, where it will be seen that in the use of the device the blanks are placed with the top edges against the guards 10 and side edges against the guards 11, and the sheets are then pressed upon the sharp pegs 12, or may have perforations for said pegs and after the sheets are thus placed the guard plate 13 is brought against them and the arms 5 engaged in the hooks 7. The operator may then mark or check upon the front sheet of the bunch 15 any memoranda or record of his work during the different time units of the day without staining the record sheet with his hands since the guard plate 13 prevents their contact with the paper. At the end of the day the guard 13 is raised and the first sheet removed to the office employing the workman, and the guard folded down again upon the next sheet and the latter used to record the next day's work and so on.

The blanks are held between the body board and the slanting portions 4 of the arms 5, so firmly that in a cheap form of the device the pegs 12 may be omitted, as will be further described about the modified forms.

In Fig. 1 it will be seen that the blank 15 uses a unit system of six minutes per unit indicated in a table A near the top of the blank and further down the blank has a horizontal line B of numbers 6 to 12 indicating the working hours before noon, and about half way down the blank has a similar line C showing the hours in the afternoon. Below each hour-indicating number and its space are smaller sized numbers designating the ten units in each hour, and below said unit numbers are vertical rows of spaces D in which to make suitable check marks horizontally opposite the job or work recorded in spaces E, F, G.

- In order to readily keep track of the vertical lines as the guard plate is moved away from the lines B or C, I provide the upper edge of it with a row H of numerals corresponding to those in row B, and below said row H I provide a row I corresponding to the row C on the blank. To further facilitate the finding of checking spaces upon the lower part of the blank I may provide a row 5 of numbers J near the lower edge of the guard plate. The spaces K, L, M on the blank or ticket 15 are used for the purposes there indicated, and the space N is to contain printed directions how to use the blank.
- 10 In the modification Figs. 5, 6, 7 the guards 11 are mechanically the same as in Fig. 1, but they may as in Fig. 7 be punched out of the plate 1 at 11^x and bent forward at right angles to the plate.
- 15 In Fig. 5 is shown that the roll 2 may have an extension 2^a riveted at 2^b and formed into a guard 2^c which prevents the top of the paper from flapping forward; the portion 2^d of the guard also limits the upward movement of the paper. In Fig. 6 is shown that the roll 2 may not be made integral with the body 1, but of a special metal strip 2^e secured by the rivets 2^b.
- 20 In Fig. 8 is shown that the body plate 1 may have no roll 2 and bail 3—4—5, but the flanges 8 are extended and bent over to form ledges 16 which engage bent end portions 17 of the guard plate 13^a, which is thus slidable over the record sheets 15 (shown in Fig. 8 but not in Figs. 9 and 10). In Fig. 10 is shown that the parts 16 and 17 in Fig. 9 may be formed as 16^a, 17^a in said Fig. 10.
- 25 When the device is modified as in Figs. 8, 9 or 10, the guard plate 13^a or 13^b is slid downward as may be necessary while the paper sheets are placed in position and then slid upward to the desired starting position for recording, and when a sheet is to be removed the guard plate is first moved partly downward and then the top end of the sheet disengaged from the pegs 12 and the sheet pulled out of the device, or the guard 13 may be moved fully downward and the sheet lifted away.
- 30 In the simplest form of the device, as shown in Fig. 11, the bar 13^c has only one end guided by a single round bar 5^x fixed at both ends to the body plate 1, while in the

other forms guiding means are provided at both ends of bar 13 or 13^a or 13^b.

55

Whenever any regular or extra ruling on the paper is required, the top or bottom edge of the guard 13 or 13^a, 13^b or 13^c is ready as a guide for the ruling pencil or pen across any part of the paper.

60

Having thus described my invention, what I claim is:

1. In a device of the class described, a body plate adapted to support paper sheets to be written on, and having means for holding the paper in place on the plate, and parallel guides near its vertical edges, a resilient guard plate for the hand to rest on while writing, said guard plate extending across the body plate and having its ends engaged to slide up and down on the parallel guides thereof.
2. The structure specified in claim 1, one or more edges of said guard plate being straight in horizontal direction.
3. The structure specified in claim 1, and means on the guard plate to engage in moving it.
4. The structure specified in claim 1, and record paper sheets held in the device and having vertical numbered lines to provide recording spaces, and said guard plate having near one or both of its horizontal edges numbers corresponding to the numbers marked at the vertical lines on the sheet.
5. The structure specified in claim 1, said body plate having an arched wire hingedly attached to the top end of the plate and formed with portions pressing the paper against the body plate and with two parallel downwardly extended arms constituting the parallel guides for the guard plate to slide on, and catches on the body plate to engage the lower ends of said arms and hold them near the said body plate.
6. In a device of the class described, a body plate adapted to support paper sheets to be written on, means for holding the paper in place on the plate, a resilient guard plate for the hand to rest on while writing, said guard plate extending across the body plate and means fixed on the body plate for guiding said guard plate in a vertical movement on the body plate.
